UNITED STATES PATENT OFFICE.

ROBERTO HEYDRICH Y MARTINEZ, OF HABANA, CUBA.

CLOSET TANK.

Application filed June 17, 1925. Serial No. 37,829.

To all whom it may concern:

Be it known that I, ROBERTO HEYDRICH Y MARTINEZ, citizen of the Republic of Cuba, residing at Habana, Cuba, have invented 5 certain new and useful Improvements in Closet Tanks, of which the following is a specification.

This invention refers to closet tanks and especially to closet tanks of the lower type, 10 although said invention can be applied to tanks of the high type with slight modifications without affecting the essential idea of the invention, and has for its main object the providing of a modification in the construction of tanks of this kind which avoids joints, packing etc. and makes the discharging of same take place by mechanical means when wished, emptying the tank totally and avoiding leaks or continued loss of water 15 and also the frequent and untimely discharge of the tank which is caused by defects in the valvular system of same.

More advantages and other considerations pertaining to this invention will be known 20 in the course of this specification, especially by those experts in the art to which same pertains and by the aid of the figures in the attached drawings in which the same character of reference designate the same parts.

25 In the drawings:

Figure 1 is an upper plan view of a closet and closet tank constructed in accordance with this invention.

Figure 2 is a longitudinal vertical section according to lines 2—2 of Figure 1.

Figure 3 is a partial sectional view in detail of the tank showing by dotted lines a working position of the parts.

Figures 4 and 5 are detailed views, partial 40 and in perspective of the cooperating parts of the tank.

In the drawings is shown by #1, a closet tank of any approved construction, which rearwardly presents an opening 2 into which projects the upper end of the shortest branch 3 of a trap the longest branch 4 of which is connected at its upper end to a pipe 5 connected to a bored opening in the bottom 45 of the tank 6.

The pipe 5 in its upper end is connected 50 to a device as is shown in detail in Fig. 4 of the drawings and consists of a funnel 7 which terminates lowerly in a threaded neck 8 to be screwed to the upper end of the pipe 5; and screwed outerly on this neck to the tank 6 is a washer 9' which cooperates with

a plate 9 integral with the funnel forming a water tight seal.

From the plate 9 extend in diametrically opposite directions, an arm 10 ending in an enlargement with an eyelet 10' and a supporting member 11 which ends in a seating plate 11'. On the end of the arm 10 is pivoted a semi-spherical bell 12 provided for this purpose with hanging ears 12' which presents bores 12'' registering with the bore 10' through which is passed a pin 13, and the bell 12 bearing upon the plate 11' in the closing position shown in Fig. 2, and having near its edges a plurality of spaced 70 bores 14, the object of which will be explained further along.

From the body of the bell 12, projects outwardly two ears 12''' between which is pivoted the lower end of a rod 15 and connected on its upper end is an angular lever 16 mounted through a hub 17 which passes through the front wall of the tank 6 and said lever ending outerly in a handle 18 for operating same.

Numeral 19 designates the pipe through which the water flows into the tank 6.

The operation of this tank is as explained below.

Supposing the tank 6 to be filled with water and the bell 12 bearing upon the support 11' of the part 11 and the trap 3—4 filled, that is with its branches 3 and 4 filled with water, all as shown in Figures 2 and 3.

Under these conditions the air into the bell 12 and filling the pipe 5 will form a 90 pneumatic closing, preventing the water contained in the tank from entering the funnel 7.

But if the handle 18 is operated causing 95 the rod 15 to be pushed upwardly, this will drag the bell 12 along and raising same as indicated by dotted lines in Fig. 3, the water will flow into the funnel 7 and form a continuous current in the trap 3—4 discharging into the tank 1 through the opening 2 and which current will continue even when the bell is allowed to drop, when ceasing to operate the handle 18, and discharging all 100 the water contained in the tank 6.

While the tank is being refilled, the water 110 when descending under the bores 14 in the bell 12 will leave them uncovered and of course, the vacuum under the bell will be broken and the bell will fill with air. The bores 14 will be hydraulically closed when the level of the water which flows through

pipe 19 into the tank rises, causing the pneumatic closure which prevents the water which fills the tank from flowing into the funnel 7.

Having thus fully described the invention, what is claimed is:

A flush tank mechanism comprising in combination with a tank, a pipe extending upwardly in and terminating slightly above, the bottom of the tank and having an expanding open upper end; a hinged plain hemispherical bell for covering the open upper end of the pipe; and means, arranged within the tank and operable from outside

the tank, to raise the bell on its hinge, a series of perforations in the bell and above 15 the lower edge thereof, a support integral with and projecting from the pipe, ears on the support for hingedly receiving the bell, and a shelf on the support to receive the edge of the bell when it is in its lowered position and screw threads on the pipe for connecting it to the tank.

In testimony whereof I have signed my name to this specification.

ROBERTO HEYDRICH y MARTINEZ.
